WELDING TORCH

Allen A. Fogelstrom, Sun Valley, Calif., assignor to SSP Industries, Burbank, Calif., a corporation of California

Filed July 30, 1969, Ser. No. 18,474

Term of patent 14 years

Int. Cl. D8—02

U.S. Cl. D8—30

FIG. 1 is a perspective view of a welding torch, showing my new design;

FIG. 2 is a top plan view of the design;

FIG. 3 is a side elevational view of the design opposite the side illustrated in FIGURE 1;

FIG. 4 is a bottom plan view of the design;

FIG. 5 is a front end view of the design taken from the left of FIGURE 1; and

FIG. 6 is a back end view of the design taken from the right hand end of FIGURE 1.

I claim:

The ornamental design for a welding torch, substantially as shown.
